UNITED STATES PATENT OFFICE.

GEORGE RIEDEL, OF GLOGAU, GERMANY.

MACHINE FOR PRODUCING FUR-RESEMBLING MATERIALS.

1,034,836.

Specification of Letters Patent.

Patented Aug. 6, 1912.

Application filed April 8, 1909. Serial No. 488,731.

To all whom it may concern:

Be it known that I, GEORGE RIEDEL, a subject of the German Emperor, and resident of Glogau, Vorstadt, Germany, have 5 invented a Machine for Producing Fur-Resembling Materials, of which the following is a specification.

The subject of this invention is a novel machine for producing artificial fur fabrics 10 by thoroughly combining the woven materials with animal hair by a treatment with reciprocatory pressing rollers and damp heat so that a thorough union of the hair and material is produced.

15 In the accompanying drawing, Figure 1 is a side elevation of the machine, Fig. 2 is a plan, Fig. 3 is a fragmental longitudinal sectional view on an enlarged scale, and Fig. 4 is a similar transverse sectional view.

20 Referring more particularly to the drawing, the standards A are shown supporting a pair of guides B provided with supporting rollers g. Upon these rollers g is slidably mounted the lower frame n, which normally supports the upper frame n¹. Across 25 each of said frames is stretched a piece of linen r between which is placed the cloth c and the hair f to be united. Sprocket wheels t are rotatably mounted at opposite ends of 30 the machine, while a drive-sprocket t¹ under the machine is mounted on the drive-shaft t² carrying the fast- loose- and reverse-pulleys t³. Over these sprocket-wheels is passed the chain t⁴ secured to the lower frame n. By 35 means of suitable belts engaging the pulleys t³ the frames n n¹ may be moved forward and backward on the tracks B.

In the middle of the machine, under the frames n n¹, is the damping chamber or 40 box d the upper part of which consists of a perforated brass plate d¹ over which the linen r glides. A pipe d² conducts steam into this chamber.

Above the pieces of linen r are two rubber 45 covered wooden rollers h having end spin-dles journaled in the supporting bars a¹ pivotally carried on the bracket a. The horizontal lower end of the bracket is secured to the beam v reciprocated by the revolving 50 eccentric v¹ and slides in a shoe e supported on one arm of the bell-crank lever e¹, the other arm of the bell-crank lever being connected by the link e² to the hand lever e³. By drawing back the hand lever e³ the shoe 55 e is raised causing the rollers h to be raised about forty centimeters above the frames

n n¹ to permit the moving of the frame to the end of the guides B so that said frames may be opened apart for the insertion or removal of the material operated upon.

60 The operation of the machine is as follows: The material, the woolen cheviot for instance, which is to be given the character of fur, is placed on the raw hair of a rabbit or other animal and the same placed between the layers of linen r and moved under the rollers h. The frames n n¹ are then carried 65 backward and forward interruptedly for any desired length of time, at the same time the rollers h being rapidly driven backward 70 and forward press against the linen r and indirectly on the material and hair therebetween. While this is going on the steam passes through the perforated plate d¹ and penetrates the various layers of cloth and hair. This operation causes the combination 75 between the cloth and hair. The pressure of the rollers h may be varied by adjusting the hand lever e³.

80 The size of the material treated is limited only by the size of the frames n n¹ which may be of any desired suitable dimensions.

I claim as new:

1. In a machine for producing fur-resembling materials, the combination of a movable frame having upper and lower cloths spaced from each other and adapted to receive the material to be felted and the fur therebetween, a movable pressing means acting on one of the cloths, and a stationary 85 moistening device supporting the lower cloth and adapted to receive steam under pressure whereby the fur is blown into the material to be felted.

2. In a machine for producing fur-resembling materials, the combination of an upper and a lower spaced pervious cloth adapted to retain therebetween an upper layer of woven fabric to be felted and a lower layer of hair, and a stationary perforated damping box below the lower pervious cloth and adapted to receive steam under pressure whereby the fur is blown into the material to be felted.

95 3. In a machine for producing fur-resembling material, a pair of longitudinal guides, a pair of superposed frames movable in said guides, linen coverings for said frames, adapted to receive between them fur and the material to be felted, sprocket wheels on said 100 guides, a chain passed over said wheels and secured to one of the frames, means for driv-

ing one of the sprocket wheels, a pair of rollers movable over the upper of said linen coverings, means for raising and lowering said rollers, means for longitudinally reciprocating said rollers, a damping box having a perforated top under the lower of said linen coverings, said damping box being adapted to receive steam under pressure whereby the fur is blown into the material

to be felted, and a pipe for conducting steam to the damping box.

In testimony whereof I have hereunto set my hand in the presence of two subscribing witnesses.

GEORGE RIEDEL.

Witnesses:
